[57] CLAIM

The ornamental design for a battery charging unit for a
portable radio or similar article, substantially as shown
and described.

DESCRIPTION

FIG. 1 is a top perspective view showing the top, front
and left side of the battery charging unit for a portable
radio or similar article.

The undisclosed front and side of the recessed area is a
mirror image of the side and rear respectively and the
bottom thereof is flat and unornamented.

FIG. 2 is a right side elevation view thereof;

FIG. 3 is a rear elevation view thereof; and

FIG. 4 is a bottom plan view thereof.
